VALVE MECHANISM

Application filed August 29, 1927. Serial No. 216,275.

This invention relates to valve mechanism for air compressors and has for its primary object the provision of a new and novel and positively functioning structure characterized by instrumentalities that render the structure useful either as an inlet valve means or an outlet valve means for the compressor, and wherein two of said valve means will function in the system in time with regular operations thereof by simply inversely positioning one of said valve means with respect to the position of the other said means without the necessity of changing the physical construction of either of said means.

15 A further object of the invention is to provide a valve mechanism which will be positive of action, simple of operation, strong and durable and of a design that insures its long life while in service.

20 A further object of the invention is to provide valve mechanism whose valve will be always definitely related to its co-acting seats and wherein the valve and said seats can be manually ground by manual operations of 25 the valve.

Other objects and advantages will more clearly appear as the description proceeds.

In the drawings:

Figure 1 is a view in side elevation of an 30 air compressor with parts in section illustrating an application of my invention thereto;

Figure 2 is a view in side elevation of the valve mechanism;

Figure 3 is a view looking toward one end 35 of the mechanism;

Figure 4 is a vertical section through the mechanism;

Figure 5 is a horizontal section on line 5-5 of Figure 4;

40 Figure 6 is a perspective view of the valve disk;

Figure 7 is a similar, but inverted, view of said disk.

In carrying the invention into practice, use 45 is made of a mechanism 10 consisting of two mating elements 11 and 12, which are threadedly connected at 13 for the accommodation of one element within the other, as shown to advantage in Figure 4. The adjustment of 50 one of said elements within the mating ele-

ment is limited through the provision of an annular flange 14 on the element 11, the same adapted to come in contact with one edge of the annular wall of the element 12. This causes a space 15 to be provided between the 55 two elements, when they are operatively related as shown in said Figure 4.

The element 11 is formed with an axial port-way 16 and a plurality of radial port-ways 17. The said element is provided with 60 a reduced annular skirt 18 which is spaced from the annular wall of the element 12 at one side of the aforeskated radial port-ways. This skirt is also provided with an annular cup or depression 19 and at the joinder of the 65 walls of the cup with the body of the element 11 there is formed a flat valve seat 20 disposed in concentric relation to the port-way 16.

The element 12 is formed with an axial port-way 21 and a valve seat 22, the latter 70 located in suitable spaced relation to the valve seat 20, so as to permit a disk-like valve 23 to function in the space between the companion valve seats. It will be observed that this disk valve traverses the mating port-ways 16 and 75 21, so that on one stroke of the piston of the compressor the disk will close against one of the valve seats and vacate the other said seat and vice-versa. The construction of the valve 80 mechanism is such that the valve disk may be manipulated manually by means of a suitable tool inserted in either of the port-ways 16 or 21 in order that it can be moved against either one of the valve seats to grind same and thereby insure a perfect seating action during 85 the operations of the compressor. In order that this can be accomplished, it is desirable to supply the disks with a stud 24 having a kerf 25 for the insertion of the aforementioned instrument.

90 From the nature of the mechanism, taken in conjunction with the characterizing features of the parts as above explained, it manifestly follows that the mechanism can be used as an illustration at the point A of the compressor as an intake valve, while a duplicate one of the mechanisms can be employed at the point B to function as an outlet. All that is necessary in order to permit the invention to perform its service in the manner stated is that 95 100

two of the mechanisms shown in Figure 4 be, respectively, incorporated in the compressor with one of the mechanisms positioned in an inverse order to the other. In the customary cycle of operation of the compressor, the disk valve 23 functions with respect to the mating seats 20 and 22 so as to, in the one instance, close the two axial ports 18 and 21 with respect to each other, and, in the second instance, to establish communication between these ports by way of the space 15, the radial ports 17, and the annular space between the walls of the element 12 and the walls of the skirt 19. A valve disk 28 of the nature recited herein may be of relatively large seating areas and the disk has been found to be capable of maximum abuse in service without disorganizing the functioning of the mechanism.

I claim as my invention:

- 20 A reversible valve for air compressors comprising a cup shaped element having an axially disposed duct therethrough and a flat annular valve seat interiorly thereof and surrounding the inner end of said duct, a second element separably connected to the first element and having a relatively shallow cup shaped portion projecting into the first element in spaced relation to the latter to provide an annular passage between the first element and cup shaped portion of the second element, the second element having a duct therethrough, axially aligned with said duct of the first element, and provided with a series of radial ports communicating at their ends directly with the annular passage and with said duct of the second element, the second element having a flat annular seat within its cup shaped portion and in surrounding relation to the inner end of its duct, and an imperforate substantially disk shaped body constituting a valve, and slidably mounted in said cup shaped portion of the second element to occupy one extreme position wherein one side face of the valve engages said seat of the second element to close the inner end of the duct of the second element so that air under pressure from the duct of the first element will be free to enter said annular passage and discharge into the duct of the second element only through said radial ports, the valve being movable to another extreme position wherein its opposite side face engages the valve seat of the first mentioned element, to thereby prevent the backflow of air from the duct of the second element to the duct of the first element.

ELMER F. SEAGER.
